(57) **CLAIM**

The ornamental design for a sidewall protector for steel coils, as shown and described.

DESCRIPTION

FIG. 1 is a reduced perspective view of a sidewall protector for steel coils in a folded position, the top portion shown engaging with the top surface of a steel coil and forming a flat bottom portion shown mating with the flat side of the steel coil;

FIG. 2 is a top plan view thereof;

FIG. 3 is a front view thereof, showing the rounded top edges as it would appear engaged with the radial top surface of a steel coil;

FIG. 4 is a side view thereof;

FIG. 5 is a front view thereof, in an open, unfolded position, where the top portion and bottom portion are planar; and, FIG. 6 is a reduced perspective view thereof, shown in folded condition forming the bendable top portion shown engaging with and conforming to a radial top surface of a steel coil and forming the flat bottom portion shown engaging and mating with a flat side surface of a steel coil.

The dotted lines on the claimed design in FIGS. 1, 2, 3, 5, and 6 represent fold lines. The bottom edge shown in broken lines in FIGS. 1, 3, 5 and 6 represents a boundary line. The steel coil shown in broken lines in FIG. 1 and 6 is for illustrative purposes only, and forms no part of the claimed design.
